UNITED STATES PATENT OFFICE.

EDWARD F. ASTLEY, OF CHICAGO, ILLINOIS, ASSIGNOR TO HUMBOLDT M. SEYER, OF CHICAGO, ILLINOIS.

BRUSH.

Application filed March 7, 1927. Serial No. 173,378.

This invention relates to brushes and has for its object to provide a new and improved device of this description.

The invention has as a further object to provide a brush which is provided with a continuous supply of liquid to be applied by the brush.

The invention has a further object to provide a brush with means for regulating the supply of the liquid to the brush.

The invention has further objects which are more particularly pointed out in the accompanying description.

Referring now to the drawings, Fig. 1 is a view of one form of brush embodying the invention.

Fig. 2 is an enlarged longitudinal, sectional view of the brush shown in Fig. 1.

Fig. 3 is a view similar to Fig. 2 illustrating the position of the parts when the brush is being used.

Fig. 4 is an enlarged sectional view taken on line 4—4 of Fig. 3.

Like numerals refer to like parts throughout the several figures.

Referring now to the drawings, I have shown a brush provided with a handle made up of removable sections 1 and 2, the sections being hollow so as to form a receptacle 30 for the liquid to be supplied to the brush. The handle is provided at its end with an opening 3 through which projects the liquid applying member 4. The applying member 4 is connected with a movable member 5 which is movable with relation to the handle. The applying member is preferably provided with a rigid end 6 which engages a stop 7 so as to limit the upward movement of the applying member.

40 The movable member 5 is provided with the cup 8 the wall of which engages the inner wall of the handle when the brush is not in use, as shown in Fig. 2. The movable member 5 is provided with one or more openings 9 through which the liquid may pass to the applying member 4. The movable member 5 is provided with a retracting spring 10 which normally holds the cup 8 against the wall of the handle. This spring 50 at one end engages a suitable stop as, for example, the stop 7 and at the other end engages a stationary part 11 which is bent at an angle, the end 12 projecting into the spring and the end 13 being connected with the handle. The sections 1 and 2 of the

handle are connected together by screw threads as shown at 14.

When the device is not in use, the section 2 may be removed and a closing cap substituted therefor so as to hold the liquid 60 in the section 1 of the handle.

I have described in detail a particular construction embodying the invention but, it is, of course, evident that the construction may be varied in many particulars without departing from the spirit of the invention as embodied in the claims hereto appended and I, therefore, do not limit myself to the particular construction shown.

In the use of the device, the liquid to 70 be applied is placed in the handle by disconnecting the section 2 from the section 1. The liquid applying member is placed in the movable member 5 and the movable member is then placed in the section 2, the 75 applying member projecting through the opening 3. The section 2 is then attached to the section 1, the end 12 of the part 11 projecting into the spring, as shown in Fig. 2. The handle is now turned to the applying 80 position and the liquid passes down into the section 2 of the handle and into the cup 8, the contact of the cup 8 with the handle, preventing the leaking of the liquid.

The liquid passes into the openings 9 and into the applying member 4. As the applying member is applied to the surface to be coated, pressure is applied to the handle and this causes the cup 8 to move inwardly so as to provide a slight opening between the cup and the inner surface of the handle so that additional liquid may pass through such opening to the applying member 4.

This position of the parts is shown in Fig. 3. When the pressure is released, the spring 10 moves the parts back to the position shown in Fig. 2. It will thus be seen that by means of this device, any suitable 100 material may be applied by the applying member 4, this material being continuously supplied to the applying member.

This construction may be used with any type of applying member and is particularly 105 adapted to a soft and flexible applying member.

I claim:

1. A brush comprising a hollow handle, providing a liquid receptacle, said handle 110

being provided with an opening, a movable member projecting into said handle, a cup on the end of said movable member which normally closes the opening in the handle,
5 an applying member extending into said movable member, the end thereof projecting from said cup, and an opening in said movable member for permitting the liquid in the receptacle to come into contact with said
10 flexible member.

2. A brush comprising a hollow handle providing a liquid receptacle, said handle being provided with an opening, a movable member projecting into said handle, a cup on the end of said movable member which normally closes the opening in the handle, an applying member extending into said movable member, the end thereof projecting from said cup, and means for elastically
15 20 pressing said cup toward the opening in said handle.

3. A brush comprising a hollow handle providing a liquid receptacle, said handle being provided with an opening, a movable member projecting into said handle, a cup on the end of said movable member which normally closes the opening in the handle, an applying member extending into said movable member, the end thereof projecting from said cup, a stop associated with said movable member for limiting the inward movement of the movable member, and a spring in said movable member, said spring arranged to be compressed when the applying member is brought into contact with the surface in connection with which it is used.

Signed at Chicago, county of Cook, and State of Illinois, this 19th day of February, 1927.

EDWARD F. ASTLEY
